UNITED STATES PATENT OFFICE.

ERNEST STUART DANIELS, OF WASHINGTON, DISTRICT OF COLUMBIA.

SPLINE-FEEDING HOPPER AND STACKER.

Application filed January 13, 1925. Serial No. 2,177.

To all whom it may concern:

Be it known that I, ERNEST STUART DANIELS, a subject of the King of England, residing at Washington, in the District of Co-

lumbia, have invented certain new and useful Improvements in Spline-Feeding Hoppers and Stackers; and I do hereby declare the following to be a full, clear, and exact description of the invention, such as will 5 enable others skilled in the art to which it appertains to make and use the same.

This invention relates to automatic feeding devices and more particularly to hoppers for orderly arranging, stacking and delivering different articles at a desired point of discharge for collective removal or successive feeding therefrom, the same being applicable to various uses although designed especially for use on machines of the character shown and described in my Patent No. 1,491,679 granted April 22, 1924, for improvements in automatic trimming, grooving and strip-inserting machines.

The principal object is to provide an automatically operable device or hopper for properly arranging, stacking and discharging articles which are irregularly deposited therein or supplied thereto in a confused or disorderly manner.

A particularly important object of such a device is the provision of novel mechanical means for aligning, stacking and feeding wooden strips or splines to position in a machine of the type referred to above, for pressure insertion into the opposed kerfed or grooved edges of planking and boards to form composite box-end or floor panel sections, or to strengthen and reinforce the same, said means for such purpose, being 25 designed to replace the narrow spline hoppers heretofore employed, thereby eliminating the laborious necessity for continuously and carefully feeding the same by hand during operation of the machine.

Simplicity in design, efficiency in operation and inexpensive in cost of manufacture, are further desiderata which have been borne in mind in the production of my improved feeding device or hopper.

The invention will be first hereinafter more particularly described with reference to the

accompanying drawings, which are to be taken as a part of this specification and then pointed out in the claims at the end of the description.

In said drawings, Fig. 1 is a perspective view of a grooving and strip inserting machine showing a cooperantly opposed pair of my improved feeding hoppers properly mounted in place thereon;

Fig. 2 is a plan view of the right hand hopper;

Fig. 3 is a central sectional elevation of said hopper, taken on the line 3—3 of Fig. 2, a number of shooks or splines being sectionally shown therein;

Fig. 4 is a front elevational view of the left hand hopper; and

Fig. 5 is an end sectional elevation thereof, taken on the line 5—5 of Fig. 2.

Referring to the drawings in which like reference numerals are used to indicate corresponding parts throughout the several views, 6 and 7 respectively denote the pedestal and work platform or table of an automatic grooving and strip inserting machine, upon which cooperant spline feeding hoppers 8 embodying the present invention,

are adjustably mounted in opposed relation to each other, said hoppers being of open-ended box-like form and preferably adapted to extension in length or breadth as shown.

Since the details of construction, arrangement of parts, and operation of the two hoppers are substantially identical, the further description of a single hopper will suffice for both.

Opposed parallel ledges or platform slide portions 9 are provided on the inner walls of the hopper, said ledges being precipitously inclined from the top brace at the rear, toward the bottom plate or wall 10 at the front thereof, with their lowermost ends spaced adjacently apart from the wall so as to provide an intervening gap or passage

therebetween, said ends being recedingly beveled as shown, for a purpose which will hereinafter appear. Forwardly extending curved guide plates 11 are underlyingly secured to the lowermost ends of said ledges

with their depending free extremities correspondingly spaced from the wall 10 in par-

allel relation thereto, thus providing a guideway or trough into which the splines or other articles deposited in the hopper, will drop one upon the other in ordered arrangement as they are successively fed therethrough. An elongated plate 12 having a concave surface confronting the lowermost ends of the ledges 9, is secured to the front wall 10 of the hopper, against which the descending splines or articles must initially impinge and deflect against the curved guide-plates 11, to prevent upsetting and cause the same to drop uniformly in horizontal position as shown in Fig. 3. The strips or articles are thus caused to stack evenly one upon the other, without possibility of resting on edge or in leaning position against either side of the guideway or trough, with consequent wedging or jamming of other strips or articles successively falling to place.

Upwardly extending parallel frame or guide-bars 13 are secured upon the inner opposed walls of the hopper in opposed linear inclination respectively to the ledges 9, said bars being intermediately bent or curved and extremally beveled with their lower portions extended downwardly in spaced parallel relation to said ledges with which the bars thus form correspondingly opposed constricting guideways for the splines or other articles fed through the hopper, the restrictive space between inclined ledge and bar being only slightly greater than the standard thickness of the articles to permit free sliding movement or passage therethrough. An extensible brace-bar 14 is secured between the upper extremities of said guide-bars to strengthen and aid in holding the latter rigidly in place.

A driven shaft 15 is supportingly journaled in the side walls of the hopper, said shaft being fixed at one end with its free end projectingly extended therethrough and provided with a keyway to permit spacing adjustment of the extensible hopper walls and associated movable parts. An ordinary gear 16 is keyed to the fixed end of said shaft for imparting rotation thereto. Corresponding rotatable discs or wheels 17 are cooperantly keyed in opposed relation upon the shaft 15 between the hopper walls with their peripheries elevated above the plane of the inclined ledges 9, and preferably in line therewith, the intervening predetermined space or gap therebetween being somewhat greater than the standard thickness of the splines or other articles to be fed through the hopper, but less than double the thickness thereof. Hub portions are formed on said discs for convenience in adjusting the same to keyed position on the shaft, and spaced radially projecting nibs or blunt-ended pins 18 are provided around the peripheries thereof, the distance therebetween being less than twice the standard width of

the splines or other articles which are to be fed through the hopper, so that only one spline or article at a time, may occupy the space between corresponding adjacent pins of the opposed discs. At diametrically opposite points substantially ninety degrees apart, the pins on the peripheries of said discs are slightly longer than the intervening pins, their projected length however, being insufficient to prevent or permanently interrupt passage of splines or articles descending the incline in proper position between the guide-bars 13 and the ledges 9, but of a length sufficient to effectually engage beneath and dislodge such splines or articles as may tend to overcrowd and jam in the constricting passageway formed by said bars and ledges. In the illustrative drawings, more particularly in Fig. 3, the pins 18 extending radially from the peripheries of the discs 17 have been shown somewhat exaggerated in size with relation to other parts, in order that their relative positions and differences in length may clearly appear, and in Fig. 3 therefore especially, the spaces momentarily remaining between the extremities of said pins and the ledges 9, when the former are moved perpendicularly to the latter, may appear insufficient or too narrow to permit the splines to move in consecutive line thereunder as indicated. In actual practice however, the shorter pins are of a length sufficient to "ride over" the descending splines without pushing them up the incline, whereas the longer pins are of a length sufficient to engage and briefly disturb or interrupt descent only of those splines that lie immediately above the point where such pins are momentarily perpendicular to said ledges. The discs when revolved, are thus adapted to act as agitators, the spaced projecting pins thereon successively disturbing or engaging and moving the overcrowding splines or articles away from the constricting passage-way beneath the discs, to prevent jamming otherwise caused by splines or articles tending to superpositely crowd into the mouth of the passage-way, the longer pins causing an intermittent impulse or "kick" of greater force than the shorter pins, thus at intervals, more effectually clearing the passage-way and forcing the splines or articles to successively descend the incline in horizontal position thereon.

An extended pivot shaft 19 is supportingly journaled in the walls of the hopper on the front side thereof substantially parallel to the shaft 15 and an extensible frame or yoke 20 is rockingly secured thereon, the latter having downwardly extended arms respectively overlying and normally resting upon the ledges 9 at an opposed inclination or angle thereto, said frame or yoke with said ledges thus forming a holder or rack

for the splines or other articles which may be haphazardly deposited or thrown into the hopper and providing a gate controlling the release of said articles down the incline. 5 Said yoke is intermittently rocked with its extended arms raised above the ledges, by means of subjacent cam-members 21 which are formed or fixed in the hub-portions of the discs 17 and adapted to engage beneath 10 the arms of the yoke as said discs are revolved to elevate the same once during each revolution of the discs, thereby releasing several of the lowermost splines or articles which may freely descend the incline toward 15 the constricted passage-way, said yoke being immediately restored to normal inclined position with its arms resting upon the ledges, by means of contracting springs 22 conveniently secured between its upper 20 cross-bar and the brace-bar 14. It will be understood that, only a few splines or articles are released during the brief intervals when said yoke is elevated above the ledges, although a number sufficient to effect a continuous 25 succession thereof on the incline beneath the discs, will be periodically released.

Spring-pressed tampers 23 having inwardly extended, depending tap-fingers, adapted to press upon and steady the splines or articles stacked one upon the other in the receptive trough, are provided on the front wall of the hopper at opposite sides thereof, said tampers being intermittently raised to permit the descending articles to fall successively in place, by means of cams 24, the latter being eccentrically keyed upon the shaft 15 and adapted liftingly to engage under the inwardly extended arm-portions 25 of said tampers, which are reciprocally movable between guides 26 secured upon the hopper walls.

Rotation is imparted to the shafts 15 of the cooperant hoppers shown in Fig. 1 of the drawings, by means of a driven shaft 27 arranged at substantially right angles thereto upon which gears 28 in mesh with the gears 16 of said shafts are keyed, the shaft 27 being provided with a key-way permitting spaced adjustment of its gears thereon and journaled in bearings carried by brackets 29 fixed to the hopper walls. Said shaft is conveniently driven from the main shaft 30 by means of a sprocket chain 31 passing over a sprocket wheel keyed upon one end thereof.

In the present illustration, the splines are successively fed or discharged from the hopper by means of push-plates 32 described in my patent hereinbefore mentioned, said plates being periodically actuated to engage and press the lowermost splines from each hopper into the opposed corresponding grooves of boards or planking 33 to form composite panels or sections of parquet flooring and box ends; although any preferred

means of discharge or removal may be employed, as my improved feeding device is not limited to use on machines of the character referred to and the articles fed thereby may be removed successively or collectively 70 as desired, the device being applicable to use in stacking and feeding various articles such as coins, packages of chewing-gum, cigarettes, candy and the like.

From the foregoing description, it will be 75 understood that I have provided a simple and efficient feeding device or hopper, into which articles may be loosely deposited or thrown without regard to order, and discharged therefrom in ordered arrangement 80 one upon the other for the purpose herein set forth, or for collective removal prior to packing in cartons, boxes or the like, and since numerous changes may be made in the details of construction and arrangement of 85 parts without departing from the spirit and scope of my invention, I do not desire to be limited by the appended claims, to the specific structure or purpose hereinbefore illustrated and described. 90

Having thus described my invention, what I claim as new and desire to secure by Letters Patent of the United States is:

1. An article feeding device comprising a receiver of box-like form having interior inclined slideways; guide-plates dependingly secured at the lower ends of said slideways in spaced relation to the front wall of the receiver to form a trough therewith; upwardly extending guide-bars secured with their lower end portions in parallel spaced relation to said slideways and forming a constricted passage-way therewith; a driven shaft journaled in the walls of said receiver; opposed discs rotatably mounted on said shaft with their peripheries above the level of said slideways and provided with spaced radially projecting pins of different lengths, the longer of said pins being adapted to engage below and momentarily prevent articles successively descending the slideways beneath said discs and the shorter of said pins being adapted to prevent overcrowding of articles into said constricted passageway; a pivot shaft; a yoke rockingly mounted thereon; and cam elements intermittently engageable with said yoke for actuating the same. 110

2. A feeding device comprising in combination; an extensible open-ended receiver of box-like form having parallel inclined slideways fixed in opposing inner walls thereof; curved guide-plates secured at the lower ends of said slideways in depending spaced relation to the front wall of said receiver to form a stacking trough therewith; upwardly extending guide-bars secured in opposed inclination to said slideways with their lower end portions in spaced parallel relation thereto and forming corresponding op- 125 130

posed constricting passage-ways therewith; a driven shaft transversely journaled in the walls of said receiver; opposed discs carried on said shaft with their peripheries above 5 the level of said slideways and provided with spaced radially projecting pins; a fixed shaft substantially parallel to said driven shaft; a yoke-frame rockingly secured thereon in opposed inclination to said slideways; 10 and cam elements movable with said discs adapted for engagement under said yoke-frame to intermittently lift and rock the same.

3. An article feeding device comprising 15 an open receiver of box-like form having inclined slideways arranged interiorly thereof; curved guide-plates secured at the lower ends of said slideways in depending spaced relation to the front wall of said receiver 20 to form an article stacking trough therewith; upwardly extending guide-bars secured in opposed inclination to said slideways with their lower end portions in parallel spaced relation thereto and forming a 25 constricting article passage-way therewith; a driven shaft transversely journaled in the walls of said receiver; opposed discs keyed on said shaft with their peripheries above the level of said slideways and provided 30 with spaced radially projecting agitator pins; a rocking shaft arranged substantially parallel to said driven shaft; a yoke-frame mounted thereon; and cam elements movable with said discs and intermittently engaging beneath said yoke-frame to lift and rock the same.

4. An article feeding and stacking device comprising in combination, an extensible open-ended receiver of box-like form having parallel downwardly inclined slide- 40 ledges secured on opposing inner walls thereof; curved guide-plates subjacently secured on the lowermost ends of said ledges in spaced depending relation to the front wall 45 of said receiver to form an article stacking trough therewith; upwardly extending guide-bars secured in opposed lineal inclination to said ledges with their lower end portions in spaced parallel relation thereto and 50 forming correspondingly opposed constricting guide-ways for the articles therebetween; a driven shaft transversely journaled in the walls of said receiver; opposed discs 55 mounted on said shaft with their peripheries above the level of said ledges and provided with spaced radially extended agitating pins below which the articles may successively descend the incline in horizontal position thereon; a fixed shaft substantially 60 parallel to said driven shaft; a yoke-frame rockingly secured thereon in opposed inclination to said ledges with its arms normally resting thereupon; and cam elements 65 carried by said discs adapted for engagement under said yoke-frame to intermit-

tently lift the same against spring action with its arms above the level of said ledges, thereby periodically releasing several of the articles restrained thereabove.

5. An article feeding and stacking device 70 comprising in combination, an extensible open-ended receiver of box-like form having parallel downwardly inclined constricting article passage-ways provided on opposed inner walls thereof; a stacking trough sub- 75 jacent the discharge ends of said passage-ways into which the articles may successively drop one upon the other; a driven shaft transversely journaled in the walls of 80 the receiver above the plane of said passage-ways; opposed disc-wheels rotatably mounted on said shaft with their peripheries spaced above the plane of said passage-ways to permit passage of the articles thereunder; spaced radially extended agitating pins fixed 85 in the peripheries of said disc-wheels below which the articles may descend the passage-ways only in succession therein; a stationary shaft fixed on the walls of said receiver above said driven shaft and substantially 90 parallel thereto; a yoke-frame rockingly mounted thereon in opposed inclination to said passage-ways with extended arms normally resting thereupon and forming an article restraining rack therewith; cam elements carried by said disc-wheels adapted 95 for engagement under said yoke-frame to intermittently lift the same against spring action with its arms above said guideways to periodically release articles restrained 100 thereabove; and means for removing the articles stacked in said trough.

6. An article feeding and stacking device comprising in combination, an extensible open-ended hopper having parallel downwardly inclined slide-ledges provided on opposed inner walls thereof; curved guide- 105 plates subjacently secured to the lower ends of said ledges in depending spaced parallel relation to the front wall of the hopper and forming an article stacking trough therewith; a rebound-plate secured upon the front wall of the hopper against which the sliding articles will initially impinge; upwardly extended guide-bars secured at opposed inclination to said ledges with their lower end portions curved backwardly in spaced parallel relation thereto and forming 110 opposed corresponding constricted guide-ways for the articles therebetween; a driven shaft journaled transversely in the walls of 115 said hopper; opposed cooperant disc-wheels mounted on said shaft with their peripheries above the plane of said ledges and provided with spaced radially extended agitating pins below which the articles may descend the inclined ledges only in succession 120 and in horizontal position thereon; a stationary shaft fixed on the hopper walls above and substantially parallel to said 125 130

driven shaft; a yoke-frame rockingly secured thereon in opposed inclination to said ledges with extended arm-portions normally resting thereupon and forming an article restraining rack therewith; cam elements carried by said disc-wheels adapted for engagement under said yoke-frame to intermit-

tently lift the same against spring action with its arms above said ledges to periodically release articles restrained thereabove; and means for removing the articles from said stacking trough. 10

In testimony whereof I affix my signature.

ERNEST STUART DANIELS.
